UNITED STATES PATENT OFFICE.

HENRY MILLER, OF SAN FRANCISCO, CALIFORNIA, ASSIGNOR TO AMERICAN CAN COMPANY, OF SAN FRANCISCO, CALIFORNIA, A CORPORATION OF NEW JERSEY.

METHOD AND APPARATUS FOR LUBRICATING PUNCHING DIES.

Application filed May 23, 1921. Serial No. 471,875.

To all whom it may concern:

Be it known that I, HENRY MILLER, a citizen of the United States, residing at the city and county of San Francisco and State of California, have invented certain new and useful Improvements in Methods and Apparatus for Lubricating Punching Dies, of which the following is a specification.

10 The present invention relates to a method and apparatus for lubricating punching or cutting dies while operating on sheets of metal and equally so for applying a lubricating medium to the surface of a sheet of metal being operated upon by the punching or cutting means; the objects of the invention being to dispense with the hand labor heretofore employed in connection with lubricating the surfaces of the sheets of metal; facilitate the operation of the punching or cutting means; prolong the life of the said means; increase the daily output of a stamping press and reduce to a minimum the work of re-sharpening the cutting edges 25 of the operating dies of the press.

In the operation of stamping presses using sharp edged dies for cutting and forming blanks for can covers and drawn seamless boxes and other operations on sheet metal, it is desirable to lubricate the sheets from which these parts are cut, which lubrication is carried to the cutting edges and surfaces of the dies to make their operation easier, to prolong their life, and to materially increase the output and reduce the necessity of sharpening or dressing their surfaces, which operation requires their removal from the press and the suspension of operation during this period, or at least 30 for the replacement of the dull and worn dies by others.

The lubrication of the sheets has heretofore usually been accomplished by hand labor, as follows:—

45 A stack of large sheets are piled on a table, an operator by means of a swab or brush carrying lubricant, goes over the entire top surface of each sheet and then places it on a new pile. It is only necessary to lubricate one side, for when the sheets are piled one on top of the other, the unlubricated side acquires enough lubricant from its surface contact with the lubricated sheet underneath.

When a large stack of lubricated sheets 55 have accumulated they are conveyed to a position near a stamping press, where an operator may pick off the uppermost sheet to present it to the cutting and forming dies.

It has been found that the natural adhesion of sheets due to the oiled surfaces interfered materially with their easy and quick removal from the pile by the press operator, and thereby were the direct cause 60 of a dropping off of the production of the press. To keep up the production it was found necessary to provide an assistant to the operator whose duty it was to separate each sheet and lay it on a table within easy 65 reach of the operator, whose sole time was then devoted to feeding the sheets through the press. In this way the output was maintained, but at the expense of an additional operator, and, furthermore, it was found in 70 the old hand method that while the lubricant might be placed ever so evenly on the sheets, the tendency, when they were piled one on top of the other, was for the lubricant to collect in little puddles on the low 75 spots, since none of the sheets ever lie exactly flat, and this was the cause of more or less of a mussy condition.

With the present method which resides in 80 subjecting the cutting edges or surfaces of the cutting dies to a spray atmosphere of lubricating medium, which is intermittently directed against the cutting surfaces of the dies of a press during the operating stroke 85 of the reciprocating cutting die, the means controlling the action of liquid spray devices being automatically actuated by the operating movement of the press, the sheet of metal to be punched being lubricated by 90 said spray of lubricating medium progressively as advanced through the press and over the area just adjacent that portion of the sheet from which the blank is to be immediately cut, whereby the surface of the sheet is left substantially dry except where 95 being acted on by the cutting means of the press and the lubricant is placed just where it is wanted and in just the quantity desired.

An apparatus for the carrying out of the 100 described method invention is disclosed by the accompanying drawings, wherein—

Figure 1 is a view showing the general

arrangement of the automatic lubricating device as applied to a press equipped for drawing seamless boxes.

Figure 2 is an enlarged view of that part of the mechanism adjacent the power shaft of the press from which it is actuated as the press operates.

Figure 3 is an enlarged view of the circular pipe forming the lubricating head from which the lubricant is sprayed onto the sheet just before cutting and on the dies just after the cut and is taken on a line 3-3 of Fig. 1.

In this improved lubricating device for the carrying out of the method invention, the lubricant is applied to the sheet in the form of a fine spray, just after it is placed in position between the dies and just before the dies come together to cut the blank from which the parts are to be drawn; the lubricating material being conveyed to the press through suitable pipes and is let into an air pipe that carries a pressure of about 15 pounds to the square inch. Above the connection where the lubricant enters the air pipe is a valve that is normally held closed by means of springs under tension, engaging opposite sides of a valve arm. Suitable tripping devices are arranged on the end of the power shaft and so placed that as the shaft revolves, one of the tripping devices engages the end of the valve arm and momentarily opens the valve, producing an instantaneous spray on the sheet and end of the punch just as the punch approaches the sheet to cut the blank, then just as the punch starts on its up stroke and has cleared the sheet the other tripping device on the end of the power shaft momentarily opens the air valve and the lower die is sprayed with lubricant through the hole in the sheet before the operator has time to move the sheet to the next position.

It is to be understood that in the operation of presses of this character, the movement of the punch is controlled by a foot treadle the treadle being pressed only when the sheet is properly placed for the next cut.

The total time of one revolution of the power shaft, if timed at the rate of 100 strokes per minute with the press running continuously would be three-fifths of a second, so that the total time of each cut will be three fifths of a second each time the press is tripped. If the press is tripped once in two seconds the operator has one and two fifths seconds in which to shift the sheet and place it against the gages to produce an output of thirty parts per minute, and some operators are skillful enough to produce upwards of 100 parts per minute, in which case the spraying is done so quickly that the operator is hardly quick enough to move the sheet after the cut and before the last spraying is done, which permits the spray

of lubricant to go through the hole in the sheet and cover the die.

In the drawings, the numeral 1 is used to indicate the top or frame of any suitably constructed press and to which is held the lower stationary die or punch 2. The upper die or punch 3 is secured or carried by the cross head of the press and the same constitutes the reciprocating cutting member which co-acts with the fixed die or punch 2, as usual in this type of machinery.

Situated above and located adjacent the lower die or punch 2 is arranged a spray head 4, the same comprising in the present case, a circular disposed pipe which is held or secured in any suitable manner to the frame of the press and so disposed as to substantially surround the lower end portion of the reciprocating die or punch 3 and through which the said die or punch works on its downward and upward strokes as moved toward and from the fixed die or punch 2. The said spray head 4 is provided with a series of outlet orifices or perforations 4' through which a lubricating medium is forced under pressure onto and against the cutting edges or surfaces of the dies or punches 2 and 3 during the reciprocating movement of the punch 3.

From the air pressure supply pipe 6 is extended a flexible connection 5, which connection at its lower end is attached to the distributing members 5' connected with and extended from the extremities of the spray head 4.

With the air pipe 6 communicates a lubricating supply pipe 7, which pipe is provided with a check valve 8 to prevent the air pressure from blowing back to an oil supply tank (not shown).

An air supply pipe is extended from a source of pressure (not shown), and said supply pipe is provided with an air valve 9 from which is extended an arm or handle 10. This arm or handle is operated to throw the valve 9 by means of the spaced trip devices 11 and 12 secured to the end of the power shaft 13, and which, during the rotary movement of the said shaft, operate to throw the arm 10 to open the valve 9 in order to give two actions to the said valve. The valve 9 is normally held closed by the tension of the springs 14 and 15, which are situated on each side of the arm 10, so that when the press is turned in reverse direction during the setting and adjusting of the dies, the arm 10 will move in either direction, which would not be possible if it came against a stop on one side.

There is provided an auxiliary valve 6' in the air pipe line 6 in order to permit of the shutting off of pressure during the time the dies are changed and adjusted or the press is reversed in motion for working around the dies, whereby the flow of lubri-

cant propelling air through the air pipe line 6 is cut off.

In Fig. 1 of the drawings—the power shaft of the press is disclosed in its normal idle position with the reciprocating punch or die 3 in its uppermost position and at which time the valve handle or tripping arm 10 stands in normal position between the trip members 11 and 12.

10 During the operation of the press the shaft 13 rotating in the direction, indicated by the arrow, causes the trip member 12 carried thereby to engage the arm 10 so as to throw the same to open the air valve 9 momentarily as it passes, which will, just before the end of the shaft's rotation, be engaged by the member 11, and which will again be thrown to momentarily open the valve 9, it being understood that the valve 15 is closed as the trip devices move out of contact with the arm 10, such closure being produced by the tension of the springs 14 and 15.

Each time the valve 9 is opened, lubricant will be drawn into and forced from 25 within the pipe 6 and under pressure forced into the spray head 4 through its connection and will escape through the orifices or perforations in the spray head in the form 30 of a spray and be ejected onto the cutting edges of the dies or punches 2 and 3, and at the same time will be ejected onto the surface of the sheet of metal S, which, at such time, is positioned between the cutting 35 dies or punches.

As the material is cut or punched from the blank or sheet S on the downward stroke of the punch or die 3, and during the upward or return stroke of the said 40 die or punch 3, the air valve 9 is actuated to cause a lubricating medium to be forced into and ejected from the spray head and onto the cutting edge of the stationary die 2 through the aperture or hole in the sheet 45 S. The sheet is then advanced between the dies for the cutting of another blank therefrom, and during the downward stroke of the cutting die or punch 3, the valve 9 is tripped to cause lubricant under pressure 50 to enter within and be forced from the spray head onto the cutting edge of the said die 3, and also onto the upper surface of the sheet of metal S, so that on one stroke of the die or punch 3 the cutting 55 edge of the fixed or stationary die 2 is sprayed with a lubricant, while on the next stroke of the said cutting die or punch 3 a spray of lubricant is directed against the cutting edge thereof, and, equally so, onto the surface of the sheet of metal positioned 60 to be acted upon.

The apparatus for the carrying out of the method invention has been illustrated and described in its preferred embodiment, 65 but I do not wish to be understood as limit-

ing or confining the invention to such detailed construction of working parts, but, on the contrary, wish to be understood as claiming as broadly as the state of the art will warrant the introduction of means for 70 coacting with the reciprocating cutting punch or die and thrown into action by the movement thereof for applying a spray of lubricant or lubricating material onto the cutting edges of the dies of the press, and, 75 equally so, wish to be understood as claiming as broadly as the art will warrant, the method of lubricating the cutting edges of the dies of a punch through the medium of 80 intermittent sprays or jets of lubricant applied thereto during the operating movements of the press, and, equally so, to the surface of the sheet of metal to be acted upon.

Having thus described the invention, 85 what is claimed as new and desired to be protected by Letters Patent is:—

1. The method of lubricating the cutting members of sheet metal cutting presses, which consists in intermittently subjecting 90 the cutting members to sprays of lubricant, directed inwardly from all sides towards the longitudinal axis of said members, during the operation of the press.

2. The method of lubricating the cutting members of sheet metal cutting presses, which consists in passing the reciprocating cutting members intermittently through a spray of lubricant, and directing said spray onto the fixed cutting member of the press 100 and on to the reciprocating member at different times during the reciprocating strokes of the reciprocating cutting member.

3. The method of applying a lubricant 105 to the surface of a sheet of metal to be cut and to the cutting members of a sheet metal cutting press, which consists in applying a spray of lubricant to the fixed and movable cutting members of the press, positioning 110 a sheet to be operated upon between the cutting members, spraying the area of the sheet to be operated upon by the cutting members of the press on a reciprocating movement of the movable cutting member, cutting and forming a part from the sprayed area of the sheet, thence spraying the fixed cutting member through the opening thus formed in the sheet, advancing the sheet to a new position between the cutting members, and spraying the movable cutting member and the surface of the sheet during the movement of said member for the cutting and forming a part from said sheet.

4. The method of lubricating the fixed 125 and movable cutting members of a sheet metal cutting press, which consists in automatically spraying the said members with lubricant during the reciprocating movements of the movable cutting member, the 130

fixed member being sprayed through the opening formed by said members in the sheet.

5. The method of lubricating the fixed and movable members of a sheet metal cutting press, and lubricating the surface of the sheet, which consists in applying to the movable cutting member and to a given area of a sheet positioned between the cutting members a spray of lubricant, cutting a section from the sprayed area of the positioned sheet, spraying the fixed cutting member with a lubricant through the cut-out section of the sheet, and thence spraying the lubricant onto the movable member prior to again acting on the sheet in a changed position for cutting a section therefrom.

6. The method of lubricating the fixed and movable cutting members of a sheet metal cutting press, which consists in automatically and intermittently directing a spray of lubricant from all sides inwardly onto the cutting members during the reciprocating strokes of the movable member.

25 7. The method of lubricating the fixed and movable cutting members of sheet metal cutting presses, which consists in automatically applying to cutting faces of said members a lubricant during the reciprocating strokes of the movable member, and punching a central opening in the said sheet metal, the lubricant being applied above the surface of the sheet metal and through said opening to the lower cutting member.

35 8. The method of lubricating the fixed and movable cutting members of sheet metal cutting presses, which consists in automatically on one stroke of the movable member spraying a lubricant to the cutting face of the fixed cutting member, and then spraying the lubricant to the cutting face of the movable member on the opposing stroke of said member, whereby the faces of the cutting members are lubricated intermittently.

45 9. In a sheet metal cutting press and in combination with the fixed cutting member and the reciprocating movable cutting member thereof, a lubricating spray device situated adjacent the fixed cutting member of the press, and means automatically thrown into operation on the reciprocating movement of the movable member for admitting lubricant under pressure to the spray device for ejection therefrom onto the faces of the cutting members.

55 10. In a sheet metal cutting press and in combination with the fixed cutting member and the reciprocating movable cutting member thereof, a spray device situated above

the fixed cutting member, pressure controlled means for delivering lubricant into said spray device, and automatically operated means for controlling the action of said pressure controlled means, whereby lubricant is alternately supplied to the face of the fixed cutting member and the face of the movable cutting member.

11. A press for lubricating sheets of metal preparatory to cutting blanks therefrom, the same comprising in combination a pair of cutting and forming dies, a spray device located adjacent said dies, an air supply connection leading to said spray device for delivering thereto lubricant under pressure, an air valve situated within the air supply connection, and means for automatically actuating said valve to supply lubricant to the spray device for ejecting the same onto the faces of the cutting members during the operative movements of the press and at predetermined periods.

12. A press for lubricating sheets of metal and cutting blanks therefrom, the same comprising a pair of cutting dies, a spray device arranged adjacent said dies for applying lubricant to the faces thereof at predetermined periods, means associated with said device for supplying lubricant thereto, air controlled pressure means for delivering the lubricant through said means to the spray device, and automatically actuated devices for regulating the air pressure during the operative movements of the press.

13. A press for lubricating sheets and dies preparatory to cutting blanks therefrom, the same comprising in combination a pair of cutting dies, a spray device arranged adjacent said dies, a lubricant supply leading to said spray device, an air supply connection for leading the lubricant to the spray device, a valve controlling the air supply, a rotating member for actuating intermittently one of the cutting dies, and means carried by said member for actuating the air valve at predetermined periods during the operative movements of the press.

14. The method of lubricating the fixed and movable die members of sheet metal cutting and punching presses, which consists in directing a substantially circular spray of lubricant inward towards the longitudinal axis of said members, feeding sheets between said members and cutting out openings in the sheets and thereby giving access of said spray to the fixed cutting member.

In testimony whereof I have signed my name to this specification.

HENRY MILLER.
